A. ROZOWSKY

CANDY PACKAGE

Filed May 21, 1923

ALFRED ROZOWSKY

INVENTOR

BY

Morris Rosenblatt
ATTORNEY

UNITED STATES PATENT OFFICE.

ALFRED ROZOWSKY, OF NEW YORK, N. Y.

DESIGN FOR A CANDY PACKAGE.

Application filed May 21, 1923. Serial No. 6,235. Term of patent 3½ years.

To all whom it may concern:

Be it known that ALFRED ROZOWSKY, a citizen of the United States, and resident of the city of New York, in the county of Kings and State of New York, has invented a new, original, and ornamental Design for Candy Package, of which the following is the specification, reference being had to the accompanying drawing, forming part thereof, in which the figure is a perspective view of a candy package embodying my new design.

I claim:—

The ornamental design for a candy package as shown.

Signed at New York city, in the county of New York and State of New York, this 18 day of May, 1923.

ALFRED ROZOWSKY.
